BACK ADJUSTMENT PLATE FOR A WALKER-STROLLER

Donald W. Gill, Cincinnati, Ohio, assignor to The Frank
F. Taylor Company, Cincinnati, Ohio, a corporation of Ohio

Filed Aug. 7, 1961, Ser. No. 66,218

Term of patent 14 years

(Cl. D14—14)

FIGURE 1 is a side elevational view of a back adjustment plate for a walker-stroller showing my new design, the opposite side being a mirror image thereof;

I claim:

The ornamental design for a back adjustment plate for a walker-stroller, substantially as shown and described.
